UNITED STATES PATENT OFFICE

172,586

COMBINED TOY ROCKET AND LAUNCHER

Otto Ernst, Los Angeles, Calif.

Application August 3, 1953, Serial No. 26,239

Term of patent 3½ years

(Cl. D34—15)

To all whom it may concern:

Be it known that I, Otto Ernst, a citizen of the United States and a resident of Los Angeles, in the county of Los Angeles, State of California, have invented a new, original, and ornamental Design for a Combined Toy Rocket and Launcher, of which the following is a specification, reference being had to the accompanying drawing, forming a part thereof.

Fig. 1 is a top plan view of a combined toy rocket and launcher, showing my new design, the

rocket being omitted for convenience of illustration;

Fig. 2 is a side elevational view of the toy; and Fig. 3 is a front elevational view of the toy.

I claim:

The ornamental design for a combined toy rocket and launcher, as shown and described.
